PHILIP V. TIPPET, OF CUYAHOGA FALLS, OHIO, ASSIGNOR TO THE VAUGHN MACHINERY COMPANY, OF CUYAHOGA FALLS, OHIO, A CORPORATION OF OHIO.

WIRE-DRAWING APPARATUS.

Application filed February 9, 1925. Serial No. 7,866.

This invention, relating, as indicated, to wire drawing drums is more particularly directed to improvements in the wire gripping mechanism of such drums.

In the art of wire drawing a common type of wire drawing drum or block is the one mounted to turn about a vertical axis and having its periphery tapered inwardly from the bottom to the top of the drum, such tapered face being adapted to receive and coil a wire thereon as it comes from the reducing die. Generally such type of drum carries a vice or gripping mechanism of some kind attached to the drum by a suitable draw chain or the like whereby the starting end of the wire may be gripped so as to pull the wire through the die as the drum revolves. At the start of the drawing operation the draw chain and wire gripper are received against the side of the drum or in a recess provided therein, and it has been found that with this form of gripping mechanism there is considerable danger of the gripper flying out as the drum rotates, due to centrifugal force. The reason for the flying out from the block is primarily due to the tapered wall upon which the drawn wire is wound, the wire being lead from the die in direct line with the bottom or larger portion of the taper on the drum and the successive convolutions serving to raise the coil of wire already on the drum. As the coil of wire is moved upward upon the reduced portion of the drum it becomes slack, which condition tends to loosen the strain on the gripping mechanism and permits it to fly out from the recess.

The object of this invention is to provide in a wire drawing drum or block an improved type of gripping mechanism which is automatically prevented from displacement, i. e., from flying out of the usual recess in the drum. Such improvements consist of the use of the ordinary drum having attached thereto a draw chain carrying at its outer end a wire gripper, and of means attached to the outer end of said chain which function upon rotation of the drum to pull the chain and gripper toward the drum. Such means are designed to exert force upon said chain opposite to the natural centrifugal force caused by rotation of the drum. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a top plan view of a wire-drawing block or drum embodying the preferred form of the present invention; Fig. 2 is a developed side elevation of the recessed portion of the drum; Fig. 3 is a sectional view taken on line 3—3, Fig. 1; and Fig. 4 is a view similar to Fig. 3 showing the parts in different position.

The block or drum illustrated in the accompanying drawing consists of a central hub portion 10, a lower flange or rim 11, an up-standing flange 12 and spider ribs 13 between said hub 10 and flange 12. The hub is centrally provided with an aperture 14 for mounting the drum on a rotatable shaft 15. The flange 12 is formed at its lower portion with a substantially vertical surface 16, upon which, as usual in this type of device, the wire is first received as it comes from the reducing die, and above the surface 16 the flange 12 is tapered inwardly, as at 17, toward the top thereof.

Referring to Figs. 1 and 2, there is shown a simple type of wire gripping mechanism which functions to automatically grip the end of the wire as the drum is rotated, it being understood, however, that the specific type of wire gripper forms no part of this invention. This gripper, designated generally at 20, having a pair of gripping jaws 21 at the forward end, is attached to the drum by a flexible element, such as a draw chain 22. The flange 12 of the drum is recessed in the side thereof, in which recess the gripping mechanism may retract during the drawing operation so as to lie within the annular contour of the flange 12. This recess is shown at 23 in the drawings, and backing the same is a vertical wall 24, against which the gripping device contacts when in retracted position.

The essentials of the foregoing description comprise the construction of a well known type of wire drawing drum or block and it is to improvements in this general type of apparatus that this invention is particularly directed. As has been pointed out in the brief summary of the invention at the beginning of this specification, one of the main

objections or disadvantages of such type of wire drawing drum results from the flying out of the wire gripper when the uppermost coils of wire on the drum become slack. I provide novel means which in no way interfere with the ordinary use of the gripping device, but which co-operates therewith to prevent the same from being thrown out by centrifugal force beyond the periphery of the drum.

The illustrated form of such means comprises a pivoted arm 25 adapted to move in opposition to the direction of centrifugal force of the gripping device. This arm 25 is pivoted at one end about a pin 26 mounted in a bracket member 27, which is secured to the bottom flange 28 of the drum, carries at its outer end a sheave or pulley 30, over which is passed a flexible cable 31. One end 32 of said cable is secured in a ring 33, suitably anchored in the side of one of the ribs 13, while the other end 34 of the cable is passed through apertures 35 and 36 provided in rib 13 and wall 24, respectively, and attached to the rear side of the gripping device 20.

In operation, when the wire gripper is first attached to the lead end of the wire the mechanism described immediately above in no way deters from the handling of such gripper or of the chain 22. As seen in Fig. 4 and in dotted lines in Fig. 1, when the chain is extended from the drum the arm 25 rocks upwardly about its pivot. After the wire is gripped and the drum started in motion the initial tendency of the gripping device is to recede into the recess 23 and the arm 25 tends to

move away from the gripping device. As the drum gains in momentum and centrifugal force acts to throw the chain and gripper away from the side of the drum the counter-acting force of the weighted arm 25 serves to effectually prevent this more or less dangerous tendency of the gripping mechanism.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In mechanism of the character described, the combination of a revoluble drum, a wire gripper, means for connecting the gripper to the drum, a pivoted arm weighted to respond to gravity, a sheave at the free end of said arm, and a cable fixed to an anchorage and extending about said sheave to connect to said gripper.

2. In mechanism of the character described, the combination of a revoluble drum, a wire gripper, means for connecting the gripper to the drum, a weighted arm pivoted within the drum to swing in a vertical plane, a sheave at the free end of said arm, and a cable fixed to an anchorage in the drum above the pivot of said arm and extending about the sheave to connect to said gripper.

Signed by me, this 5th day of February, 1925.

PHILIP V. TIPPET.
